UNITED STATES PATENT OFFICE.

ANDRAS DRENOVICS, OF TAMASI, HUNGARY, ASSIGNOR OF ONE-FOURTH TO J. FABIAN
AND ONE-FOURTH TO C. SZOMBATHY, BOTH OF NEW YORK, N. Y.

PADLOCK.

Application filed May 14, 1925. Serial No. 30,345.

To all whom it may concern:

Be it known that I, ANDRAS DRENOVICS, a citizen of Hungary, residing at Tamasi, in the county of Tolna and country of Hungary, Europe, have invented certain new and useful Improvements in Padlocks, of which the following is a specification.

This invention relates to new and useful improvements in padlocks.

16 The primary object of the invention is to provide a padlock of the pivoted hasp type wherein a sliding keeper is employed for preventing opening movement of the hasp.

18 A further object of the invention is to provide a key-hole cover or guard adapted for preventing the lodging of foreign matter in the key-hole and for confusing a person attempting to open the padlock without proper authority.

20 Other objects and advantages of the invention will be apparent during the course of the following description.

25 In the accompanying drawings forming a part of this specification and in which like numerals are employed to designate like parts throughout the same,

Figure 1 is a front elevational view of a padlock embodying this invention,

30 Figure 2 is a vertical sectional view taken upon line II—II of Fig. 4, the hasp being illustrated in its closed position and being retained in such position by the sliding keeper,

35 Figure 3 is a similar view to Fig. 2 but shows the hasp moved to its opened position after the sliding keeper has been moved out of its hasp holding position,

40 Figure 4 is an edge elevational view of the padlock shown in Figs. 1 to 3 inclusive,

45 Figure 5 is a similar view to Fig. 4, but shows the application of the key and its movement for unlocking the hasp,

Figure 6 is a longitudinal sectional view taken upon line VI—VI of Fig. 5,

48 Figure 7 is a transverse sectional view taken upon line VII—VII of Fig. 5,

Figure 8 is a detail front elevational view of the keeper actuating disk,

50 Figure 9 is an edge elevational view of the keeper actuating disk,

Figure 10 is a front elevational view of the bearing cup for the keeper actuating disk,

55 Figure 11 is an edge elevational view of the bearing cup shown in Fig. 10, and

Figure 12 illustrates a front elevational view and an edge elevational view of a cover or guard plate.

In the drawings, wherein for the purpose of illustration is shown a preferred embodiment of this invention, the numeral 5 designates the padlock casing in its entirety which includes the side walls 6 and 7 and the bottom wall 8. The bottom wall is provided with a centrally located inwardly projecting boss 9 which is provided with a longitudinally extending recess 10, the function of which will be disclosed at a later point in the description. The lock casing further includes a rear plate 11 secured by the rivets 60 12, and a front plate 13 secured by the rivets 14 and having a centrally positioned circular opening 15. The top of the casing is partially closed by the permanently positioned plate 16, held in place or connected 65 to the front and rear cover plates 11 and 13 by the rivets 12 and 14.

Extending through the cover plates 11 and 13 at the corners of the same spaced longitudinally from the upper end of the side wall 7 is a pin 17 which pivotally supports the hasp 18. The pivot end of the hasp 18 is provided with a laterally inwardly offset heel 19 having a curved bottom surface 19^a adapted for bearing against the similarly curved surface 7^a of the end of the side wall 7 of the casing when the hasp is in its closed or locked position.

The hasp is retained in its closed or locked position by the sliding keeper 20 which is of substantially plate-like formation having the elongated slot 21 formed centrally therein for receiving the post 22 and tension spring 23 to be described in detail at a later point. The upper edge of the sliding keeper 25 is provided with a notch 24 and a lug 25 forming an extension of one wall of the notch. This notch 24 and lug 25 cooperate for bearing against the free end of the hasp heel 19 for preventing pivotal movement of the hasp. For the purpose of maintaining the keeper in its hasp holding position, a spiral spring 26 is seated in the recess 10 formed in the boss 9 and encircles a pin 27 depending from the bottom edge of the keeper 20 for bearing against this said bottom edge of the keeper.

Journaled in a small recess 28 formed in the rear wall 11 of the casing is a journal 29 for the post 30 which is provided with 100 105 110

a reduced square opposite end 31 fitted within a similarly shaped opening in the keeper actuating disk 32 which is positioned forwardly of the sliding keeper 20. This disk 6 has its front portion journaled within a cup-like bearing 33 having a circular opening 34 formed therein. This bearing cup 33 is received within a circular pocket 35 formed in the inner face of the front wall 13 of the 10 lock casing, which pocket also receives a circular cover or guard plate 36 which is arranged forwardly of the bearing cup 33. Encircling the post 30 and having its forward end received within a recess 37 in 15 the keeper actuating disk 32 is a spiral spring 38 which acts to force the keeper actuating disk against the bearing cup 33 and the bearing cup against the cover or guard plate 36 which in turn is forced against 20 the inner wall of the pocket 35 for preventing unintentional shifting of these elements by the frictional engagement of these members with each other.

The keeper actuating disk 32 is further 25 provided with a laterally projecting pin 39 which overlies the upper edge of the keeper 20 and constantly bears against the same. The front face of the keeper actuating disk 32 is provided with the openings 40 which 30 are arranged concentrically with the axis of the disk and are located at four equally spaced points.

By inspecting Figs. 1 and 5, it will be seen that the elongated slot 36^a formed in 35 the cover or guard plate 36 is of substantially equal length to the diameter of the openings 34 and 15 formed in the bearing cup 33 and front wall 13 respectively and that the said slot 36^a may be arranged as 40 in Fig. 1 for concealing the openings 40 in the keeper actuating disk 32 or it may be arranged to expose diametrically positioned openings 40.

The key 41 is provided with the longitudinally extending spaced lugs 42 which are spaced the proper distance to span the diametrically opposed openings 40 in the keeper actuating disk 33.

The operation of the padlock embodying 50 this invention may be described as follows:—

It will first be considered that the hasp 18 is in its closed position with the keeper 20 arranged so that the side wall of the notch 24 and the corresponding wall of the lug 25 bear against the outer end of the hasp heel 19, the said keeper being held in that position by the spiral spring 26. The cover or guard plate 36 should be arranged as in Fig. 1 with the elongated slot 36^a out of register with either of the sets of diametrically opposed openings 40 formed in the keeper actuating disk 32. To release the hasp 18, the possessor of the key 41 should insert the lugs 42 into the slot 36^a of the cover or guard plate 36 and turn the said

cover or guard plate until the slot 36^a registers with either of the diametrically opposed sets of openings 40. Then the said lugs 42 of the key 41 may be positioned within the same. By turning the key in a clockwise direction, as indicated by the arrow in Fig. 5, the keeper actuating disk 32 is caused to rotate in the same direction for moving its laterally inwardly projecting pin 39 in a clockwise direction. This movement of the pin 39, in view of its constantly bearing against the upper edge of the sliding keeper 20, will cause the latter to move downwardly through the lock casing against the pressure of the spiral spring 26. This movement of the sliding keeper 20 will continue until the pin 39 bears against the lug 25 formed on the keeper 20 which engagement will prevent further movement of the key and the actuating disk 32 and also will stop the movement of the keeper 20. The keeper, however, has been moved sufficiently to free the heel 19 of the hasp 18 from the notch 24 and lug 25 so that the hasp may be pivoted to its open 90 position, as shown in dotted lines in Fig. 5 and in full lines in Fig. 3. In Fig. 3, the heel 19 of the hasp is shown as bearing against the top plate 16 of the casing which engagement will limit the opening movement of the hasp.

It will be noted that the cover or guard plate 36, when positioned to arrange its slot 36^a in respect to the sets of diametrically opposed openings 40 of the keeper actuating disk 32, as shown in Fig. 1, will prevent the entrance of foreign matter into these key lug receiving openings 40 and will also confuse a person attempting to open the padlock without the proper authority.

It is to be understood that the form of this invention herewith shown and described is to be taken as the preferred example of the same, and that various changes in the shape, size, and arrangement of parts may 100 be resorted to without departing from the spirit of the invention or the scope of the subjoined claims.

Having thus described the invention, I 115 claim:—

1. In a padlock of the type described, a casing, a hasp pivoted to the casing and having a heel projecting inwardly thereof from its pivot end, a spring pressed slidable keeper engageably associated with the heel 120 of the hasp for holding the hasp in its closed position, a rotatable member for sliding said keeper into its hasp heel releasing position, said rotatable member having a pair of spaced key receiving openings, said casing 125 having a relatively large key-hole registering with both key openings, and a key for actuating said rotatable member.

2. In a padlock of the type described, a casing, a hasp pivoted to the casing and 130

having a heel projecting inwardly thereof from its pivot end, a spring pressed slidable keeper engageably associated with the heel of the hasp for holding the hasp in its closed position, a rotatable member for sliding said keeper into its hasp heel releasing position, said rotatable member having a pair of spaced key receiving openings, said casing having a relatively large key hole 10 registering with both key openings, a rotatable cover plate having a slot capable of being arranged in or out of register with the key openings, and a key adapted to be inserted into the slot of the cover plate for 15 arranging the slot in register with the openings in the rotatable member for permitting

the key to enter said openings to actuate said rotatable member.

3. In a padlock of the type described, a casing, a hasp pivoted to the casing and having a heel projecting inwardly thereof from its pivot end, a spring pressed slidable keeper engageably associated with the heel of the hasp for holding the hasp in its closed position, a rotatable disk for sliding said keeper into its hasp heel releasing position, a bearing cup for the rotatable disk and received within a pocket formed in the casing, and a key for actuating said rotatable disk. 20 25 30

In testimony whereof I affix my signature.
ANDRAS DRENOVICS.
